UNITED STATES PATENT OFFICE.

JOHN H. BLACK, OF NEW YORK, N. Y., ASSIGNOR TO VICTOR E. MAUGER,
OF SAME PLACE.

IMPROVEMENT IN PLAYING-CARDS.

Specification forming part of Letters Patent No. 171,978, dated January 11, 1876; application filed November 17, 1875.

To all whom it may concern:

Be it known that I, JOHN H. BLACK, of the city, county, and State of New York, have invented a new and useful Improvement in Playing-Cards, which improvement is fully set forth in the following specification, reference being had to the accompanying drawing.

The object of this invention is to produce a playing-card which, by the exposure of any one of its four corners, shall allow its suit and value to be known, whichever way it may be displayed in the hand.

My invention consists in the production of a card which has in each of its four corners a numeral, symbol, letter, or character placed near an emblem of the suit.

Figures 1 and 2 are face views of cards that have the quadruple system of numerals combined with a peculiar marginal application of emblems, all as hereinafter more fully described.

The cards A and B in the drawing are ordinary playing-cards made of quadrangular form. These cards contain in each of their corners *a*, *b*, *c*, and *d*, respectively, a numeral or letter representing value; thus, for example, the two of spades contains in each corner the numeral 2. But in order, also, to distinguish the several suits from one another—for example, to distinguish the said two of spades from the two of hearts—a miniature representation of the emblems or pips is printed near every such numeral in every corner, as shown.

As a modification, this row of pips may at each corner extend along one margin only, or it may be placed along the two margins, so

that for the ten of hearts, for example, every upper corner of the card may contain five hearts along the upper edge and five along the adjoining side, and in a similar manner the lower corners could thus be provided.

For court-cards, the letters K, Q, and J, or other convenient letters, or the representations of crowns, helmets, and caps, or other appropriate symbols, will be used in place of the numerals on the other cards; but such letters and symbols are also to be used on the quadruple system.

I am aware that a combination of a number and emblem in a corner or a side of a playing-card is not new; also, that a miniature representation of the number of spots of the card in opposite diagonal corners is old; therefore, such I do not claim.

By my invention I accomplish something beyond what has heretofore been done—namely, a means of insuring the reading of the card without exposure, except at any one of its four corners, and that equally well in the hands of right and left hand players.

I claim as my invention—

A playing-card containing in each of its four corners a numeral, word, or letter indicating its value, together with a miniature emblem or emblems indicative alike of its value, character, and suit, such emblems being also made to correspond in number with the spots on the face of the card, substantially as described and shown.

J. H. BLACK.
